DISPLAY

Richard Burdick, Dallas, Tex.

Application February 17, 1941, Serial No. 379,205

7 Claims. (Cl. 40—125)

This invention relates to new and useful improvements in displays.

The invention particularly relates to the formation of advertising displays or signs and the method or means of attaching the same to a foraminous material, such as wire mesh fabric.

One object of the invention is to provide improved means whereby characters, such as letters, figures, symbols and the like, may be economically produced and attached to an open mesh fabric, such as screen wire, which is ordinarily used in windows and doors, so as to give the appearance of being formed directly on the fabric.

An important object of the invention is to provide an improved display which includes a flexible supporting medium of foraminous or other material with a background element of similar material secured thereto by suitable fastening means, whereby the element lies contiguous to the supporting medium and appears to be integral therewith, said element having display characters applied thereto.

A particular object of the invention is to provide an improved display which includes a flexible background of foraminous or other material, having its interstices filled with a suitable substance, the background being secured to a flexible or wire mesh fabric by clips, frames, rivets or other suitable means, whereby said background snugly engages the fabric and blends therewith so as to produce the effect of being applied thereto; the use of the clips preventing independent stretching or movement of the display relative to the support, whereby buckling or bulging of said display is prevented and an attractive sign produced.

A further object of the invention is to provide an improved method of economically forming a display which consists of applying characters to a background of foraminous or pervious material and then attaching the background to a supporting medium of similar material, whereby the necessity of forming the characters directly on the supporting medium is obviated.

The construction designed to carry out the invention will be hereinafter described together with other features of the invention.

The invention will be more readily understood from a reading of the following specification and by reference to the accompanying drawings, as an example of the invention is shown, and wherein:

Figure 1 is a plan view of a display, formed in accordance with the invention.

Figure 2 is an enlarged plan view of a corner

clip for fastening the display to a wire mesh fabric.

Figure 3 is a plan view of the display fastened to the fabric by the clips.

Figure 4 is an enlarged, transverse, vertical, sectional view, taken on the line 4—4 of Figure 3.

Figure 5 is a view, similar to Figure 3, showing the display fastened to the fabric by a complementary frame.

Figure 6 is a view, similar to Figure 5, of the rear side of the fabric and showing the rear frame.

Figure 7 is an enlarged, transverse, vertical, sectional view, taken on the line 7—7 of Figure 5.

Figure 8 is a similar view, taken on the line 8—8 of Figure 5.

Figure 9 is a plan view of a slightly-modified form of the display.

Figure 10 is a plan view of the modified display fastened to a wire mesh fabric by corner clips, and

Figure 11 is a view, similar to Figure 9, showing the display fastened to the fabric by a complementary frame.

In the drawings, the numeral 10 designates a background member of open mesh fabric, such as screen wire, which has its interstices filled with a cellulose composition, paint, plastic, or other desirable substance. Although any other suitable material may be employed, it has been found that "Cel-O-Glass" is preferable due to its translucence and opalescence. The background member is preferably of a general elliptical or oval shape and is provided with a pair of angular ears or extensions 11 at each end thereof. Suitable display characters 12 are disposed on the member 10, which may be applied by stencilling, painting, by means of a decalcomania transfer, or other means.

For securing the background member to a supporting medium 13 in the nature of an open mesh wire fabric, such as wire screen which is ordinarily employed in doors and windows, a plurality of angular clips 14 of metal, or other suitable material, are provided as shown in Figure 2. The clips are complementary to the ears or extensions 11 of the background member and are preferably formed in the shape of a right-angle triangle, although the particular shape of the

same is dependent upon the configuration of said ears. The hypotenuse or long edge 15 of each triangular clip is curved or arced inwardly toward the outer corner to conform to the curvature of the edge of the member 10, while the outer perpendicular edges or margins 16 of said

clip are curved rearwardly in cross-section to provide clamping edges, as shown in Figure 4. An aperture or opening 17 is formed in the clip adjacent the outer corner for receiving a rivet 18, or other fastening means, as will be herein-after explained.

In carrying out the invention, the background member 10, with the characters 12 applied thereto, is placed upon one face of the wire mesh fabric 13 in the desired position and a clip 14 is disposed over each ear of said member. Complementary clips 19 are preferably positioned against the other or rear surface of the fabric in alinement with or parallel relationship to the clips 14 and then said clips and the background member are fastened to the fabric by the rivets 18 which extend through the openings of the clips, as is clearly shown in Figures 3 and 4. Thus, the background member is firmly secured to the fabric and, since said member is formed of screen mesh fabric having its interstices filled with a suitable material, the member appears to be formed directly on said fabric; that is, the member merges with the screen fabric and appears to be an integral part thereof.

By utilizing clips or similar means for fastening the pre-formed background member to the fabric, said member is held contiguous thereto and an attractive, economical display is provided. Of course, it is not essential that either or both of the clips 14 and 19 be employed, since the rivets 18 alone are sufficient to hold the member in place. However, the clips present amplified gripping surfaces to the member so as to snugly clamp the same to the fabric, this clamping action being most effective when both sets of clips are used which tend to prevent buckling and warping of said member. It is also pointed out that, if desired, a pair of background members may be secured back to back on each side of the fabric with a single set of either front or rear clips. Obviously, the forward clips are most important both from a utilitarian and an ornamentation standpoint.

In some instances, it has been found desirable to employ an elliptical or oval frame or 20 in place of the clips 14 for fastening the background member 10 to the wire mesh fabric 13 as shown in Figures 5 to 8. The frame is complementary to the marginal edge of the background member and is provided with angular ears 21, similar to the clips 14, which conform to the ears 11 of said member so as to overlie the same when in fastening position. As shown in Figures 7 and 8, the frame is cupped or arced in cross-section to provide a substantially semi-circular rim 22 for engaging and clamping the member 10 to the fabric 13. For engaging the rear surface of the fabric, a flat frame 23, similar to the frame 20 and having similar ears 24, is employed in place of the clips 19. However, if desired, the clips 19 could be used successfully with the frame 20. Of course the marginal edges of the forward frame, its ears 21 and the rear frame are curved inwardly in cross-section in the same manner as the clips 14 and 19, while the background member and said frames are secured to the fabric by the rivets 18 or other fastening means. Manifestly, this method of attaching the background member to the fabric materially increases the rigidity of said member.

In Figures 9 to 11, the background member has been shown as diamond-shaped or in the form of a parallelogram 25 in order to further illustrate the invention. Obviously, the particular

shape of the member is unimportant so long as the same may be attached to the supporting medium or fabric in accordance with the invention, thereby giving the appearance of being an integral part of said medium. In Figure 10, triangular clips 26 which are similar to the clips 14 and 19 have been used to fasten the member 25 to the fabric 13, while said member has been secured to said fabric by a diamond-shaped frame 27, similar to the frame 20, in Figure 11. A detailed description of the clips 26 and frame 27 is thought to be unnecessary since the same are substantially identical to the clips of the first form. However, it is noted that the particular shape of the clips varies in accordance with the form or contour of the background member. Due to the angularity of the member 25, the ears or extensions 28 of the frame 27 are disposed within the inner margin thereof instead of projecting outwardly from the same in the manner of the ears 21 of the frame 20. A complementary flat rear frame (not shown) is preferably used along with the frame 27, although the clips 26 or other means would be satisfactory.

From the foregoing, it is readily apparent that a simple, inexpensive means of displaying characters on an open mesh fabric is provided. Since the display characters are applied to a background member of "Cel-O-Glass" or other suitable material which is attached to the fabric, the same appear to be formed directly thereon, especially to the casual observer. The improvement hereinbefore set forth obviates the necessity of removing or replacing the fabric in order to apply the characters thereto and also makes it possible to change said characters from time to time without substituting another fabric. It is noted that the use of the clips or faseners make it possible to attach a sign of a material or fabric which is different from the material of which the support is formed, without the sign buckling or bulging. The clips securely fasten the sign at various points and prevent individual stretching or pulling of the sign independently of the support, whereby the sign remains substantially flat against the support throughout its period of attachment to said support.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A display including, a supporting medium of wire mesh fabric, a background element of substantially the same material as the medium so as to blend therewith when placed thereover, said element having display characters thereon, rigid metallic clamping means disposed on opposite sides of the medium and adapted to overlie portions of the background element, and means for securing the rigid clamping means to the medium whereby the display element is clamped to the medium and the medium is reinforced by said clamping means.

2. A display including, a support of ordinary wire mesh screen, a sign element formed of wire mesh screen having a display character thereon adapted to be secured to the screen, rigid clamping members disposed on opposite sides of the support and overlying portions of the sign element, and means for fastening the clamping

members to each other with the support and portions of the sign element therebetween, whereby said sign element is secured to the support and also whereby the support is reinforced and buckling thereof is prevented.

3. A display including, a support of ordinary wire mesh screen, a sign element formed of wire mesh screen having a display character thereon adapted to be secured to the screen, a rigid clamping frame on each side of the support and overlying the marginal edge portion of the sign element, and means passing through said support and said marginal edge portion of the element and secured to the two frames whereby said frames clamp the sign element to the support.

4. A display including, a support of ordinary wire mesh screen, a sign element formed of wire mesh screen having a display character thereon adapted to be secured to the screen, said sign element having integral extensions beyond the display area thereof, a plurality of clamps arranged in pairs, a pair of clamps being provided for each extension and overlying said extension on opposite sides of the support, and means for fastening each pair of clamps together with the extensions of the sign element and the support therebetween, whereby the sign is secured to the support by said clamps.

5. A display including, a support of wire mesh fabric, a sign arranged to be secured to the support and formed of a background element of wire mesh fabric, the interstices of the fabric of the

background element being filled with a cellulose composition with display characters applied thereto, rigid fastening members disposed on opposite sides of the support and overlying portions of the background element of the sign, and means for securing the fastening members to each other with the support and sign therebetween, whereby the sign is fastened to the support by said members.

10 6. A display including, a supporting medium of wire mesh fabric, a background element of substantially the same material as the medium to blend therewith when placed thereover, the element having display characters thereon, rigid metallic fastening means overlying portions of said background element, and means for securing the rigid fastening means to said medium, whereby the element is confined between said fastening means and the medium and said medium is reinforced by the fastening means.

15 7. A display including, a support of ordinary wire mesh screen, a sign element formed of wire mesh screen having a display character thereon adapted to be secured to the screen, a rigid clamping member overlying portions of the sign element, and means for fastening the clamping member to the support with portions of said sign element therebetween, whereby the sign element is secured to said support and also whereby the support is reinforced and buckling thereof is prevented.
